ANTENNA ARRAY SYNTHESIS METHOD
Carlyle J. Stetten, Acton, Mass., assignor to the United States of America as represented by the Secretary of the Air Force
Filed Oct. 10, 1956, Ser. No. 615,208
1 Claim. (Cl. 343—771)
(Granted under Title 35, U.S. Code (1952), sec. 266)

The invention described herein may be manufactured and used by or for the United States Government for governmental purposes without payment to me of any royalty thereon.

This invention relates generally to antennas and more particularly to a method of synthesizing linear antenna arrays by utilizing the natural phase distribution that exists on a transmission line. The far-field pattern function obtained with equispaced elements is decomposed in terms of the feeding coefficients realizable along the feeding guide. Such functions are sufficiently general to permit synthesis of any arbitrary pattern with arbitrary phase.

In utilizing the method of synthesis of this invention, use is made of the natural phases which occur on a feeding waveguide or transmission line to feed a linear array of any kind; the radiators are spaced about $\lambda_g/4$ apart and produce complex antenna patterns. Only amplitude, rather than both amplitude and phase, is used to control the radiated power.

Prior techniques have been more complicated and difficult to use because they involve approximating a continuous aperture distribution by means of discrete radiating elements, and, since phasing is approximately obtained by variable longitudinal spacing between elements, pattern calculation is difficult.

Accordingly, it is an object of this invention to provide a technique or method of antenna synthesis which produces more precise control of antenna beam shapes.

Another object of the invention involves the simplification of antenna designs for complex beam shapes such as are used for Ground Control Approach (GCA) search and mapping.

Still another object of the invention is the utilization of the natural phases on a feeding waveguide or transmission line to produce any desired coverage pattern.

A further object of the invention involves the production of a new antenna device based on a new method of array synthesis.

A still further object of the invention involves an antenna device wherein the relative electrical phase of a radiator is obtained from a constant longitudinal spacing together with the position of the element with respect to the center line of the antenna.

These and other advantages, features and objects of the invention will become more apparent from the following description taken in connection with the illustrative embodiments in the accompanying drawings, wherein:

FIGURE 1 is an illustration representing a linear array;

FIGURE 2 depicts a microwave antenna suitable for use in the resolution of a radiated pattern in terms of phase on a transmission line;

FIGURE 3 illustrates an ideal field pattern;

FIGURE 4 shows the pattern of FIGURE 3 broken into odd and even parts;

FIGURE 5 shows a seven slot array designed in accordance with the method of this invention; and

FIGURE 6 represents an H-plane pattern of the array of FIGURE 5.

The mathematical basis of this invention is treated as a problem in one dimension, the θ plane, although

2

with rectangular apertures the problem can often be separated into two one-dimensional problems.

FIGURE 1 shows θ measured from the normal to the array. The radiation pattern produced by a linear array of omnidirectional elements will always have even symmetry with respect to the line of the array unless the elements are made directive by a ground screen or some other device.

The required power pattern $E(\theta) \cdot E^*(\theta)$ is specified in the interval $-90^\circ \leq \theta \leq 90^\circ$. It is assumed that individual radiating elements produce identical radiation patterns and the same polarization at each point in space, that is, $E(\theta) = f(\theta) \hat{E}$, where $\hat{E}$ is a unit vector in the direction of polarization, and the complex function $f(\theta)$ is the scalar function to be generated. The complex function $f(\theta)$ is ordinarily $|f(\theta)| e^{j\gamma(\theta)}$, with the phase function $\gamma(\theta)$ being adjusted for different applications or to simplify design.

The far-field pattern of a linear array of equally spaced radiators, where the directivity of each element is $D(\theta)$, is given by

$$f(\theta) = D(\theta) \sum_{n=-N}^{n=N} R_n e^{j(\phi_n + nd\frac{2\pi\psi}{\lambda})}$$

where R_n is the amplitude of excitation, ϕ_n is the phase of excitation, λ is the wavelength, d is the element spacing, and ψ is equal to $\sin \theta$.

FIGURE 2 illustrates how $f(\theta)$ can be resolved into component functions that are simply related to phase on the feeding line. On a transmission-line shunt loaded with real admittances at nodes or anti-nodes in the standing-wave pattern, the phase increases 90° from the feeding end at each successive maximum and minimum of the transmission-line fields. When 180° phase reversal of the radiator is possible, such as is obtained by crossing the leads on a dipole or, as shown here, by placing longitudinal shunt slots on opposite sides of the center line on the broad face of a rectangular waveguide in the TE_{10} mode, the values of $e^{j\phi_n}$ can be 1, -1 , j , and $-j$.

The resolution of a radiated pattern of each elemental array of slots in FIGURE 2 in terms of phase on a transmission line may be expressed by:

$$f_u = \frac{C_2}{2} e^{-j\frac{2\pi\psi}{l}} + \frac{C_1}{2} e^{-j\frac{\pi\psi}{l}} + C_0 + \frac{C_1}{2} e^{j\frac{\pi\psi}{l}} + \frac{C_2}{2} e^{j\frac{2\pi\psi}{l}}$$

$$f_s = \frac{D_2}{2} e^{-j\frac{2\pi\psi}{l}} + \frac{D_1}{2} e^{-j\frac{\pi\psi}{l}} - \frac{D_1}{2} e^{-j\frac{\pi\psi}{l}} - \frac{D_2}{2} e^{j\frac{2\pi\psi}{l}}$$

$$f_w = -j\frac{A_1}{2} e^{-j\frac{3\pi\psi}{2l}} - j\frac{A_0}{2} e^{-j\frac{\pi\psi}{2l}} - j\frac{A_0}{2} e^{j\frac{\pi\psi}{2l}} - j\frac{A_1}{2} e^{j\frac{3\pi\psi}{2l}}$$

$$f_v = -j\frac{B_1}{2} e^{-j\frac{3\pi\psi}{2l}} - j\frac{B_0}{2} e^{-j\frac{\pi\psi}{2l}} + j\frac{B_0}{2} e^{j\frac{\pi\psi}{2l}} + j\frac{B_1}{2} e^{j\frac{3\pi\psi}{2l}}$$

where each term in each of the functions corresponds to a particular radiator and each slot in FIGURE 2 is labeled with the letter of its function; the terms to the left corresponding to the radiators shown at the left, etc.

$$f_u(\psi) = \sum_{n=0}^N C_n \cos \frac{n\pi\psi}{l} \quad N = \frac{n}{2} - 1$$

$$f_s(\psi) = -j \sum_{n=0}^N D_n \sin \frac{n\pi\psi}{l} \quad N = \frac{n}{2} - 1$$

$$f_w(\psi) = -j \sum_{n=0}^N A_n \cos \left(n + \frac{1}{2} \right) \frac{\pi\psi}{l} \quad N = \frac{n}{2} - 1$$

$$f_v(\psi) = \sum_{n=0}^N B_n \sin \left(n + \frac{1}{2} \right) \frac{\pi\psi}{l} \quad N = \frac{n}{2} - 1$$

where

$$l = \frac{\lambda}{\lambda_g} = \frac{\lambda}{2d}$$

$$\psi = \sin \theta;$$

+j is 90° lead in time; and

(N+1) is the total number of elements left or right of center of phase.

In FIGURE 2 the phase reference is the slot in the center of the array. The feeding coefficients A_n , B_n , C_n , and D_n are assumed to be real, and are adjustable by the coupling conductance g of the radiator. The phase of the element is obtained from the longitudinal spacing $d = \lambda_g/4$ and the position of the element with respect to the center line. Only the first few elements (terms) are shown, but it is clear that more can be added, in pairs, on the ends of each elementary array. The separate terms of the equations represent the pattern contributed by an element. Elements are identified and summed to illustrate how they can be combined into four simple sine and cosine series. Each of these four series is in the form of a Fourier series in $\psi = \sin \theta$ in the interval $l = \lambda/2d$. Any ideal required pattern $f(\theta)$ can be decomposed into even and odd parts since electromagnetic fields are linear and can be superposed on one another. Hence,

$$\begin{aligned} f(\theta)_{\text{ideal}} &= [f_{\text{real,even}}(\theta) + f_{\text{real,odd}}(\theta)] \\ &\quad + j[f_{\text{imag,even}}(\theta) + f_{\text{imag,odd}}(\theta)] \\ f_{\text{even}} &= \frac{1}{2} [f(\theta) + f(-\theta)] \\ f_{\text{odd}} &= \frac{1}{2} [f(\theta) - f(-\theta)] \end{aligned}$$

We can let

$$f_{r,e}(\theta) = f_u(\psi) = \sum_{n=0}^{n=N} C_n \cos \frac{n\pi\psi}{l}$$

$$f_{r,o}(\theta) = f_v(\psi) = \sum_{n=0}^{n=N} B_n \sin \frac{(n+\frac{1}{2})\pi\psi}{l}$$

$$f_{i,e}(\theta) = j f_w(\psi) = \sum_{n=0}^{n=N} A_n \cos \frac{(n+\frac{1}{2})\pi\psi}{l}$$

$$f_{i,o}(\theta) = j f_x(\psi) = \sum_{n=0}^{n=N} D_n \sin \frac{n\pi\psi}{l}$$

The degree of approximation to $f(\theta)$ will of course depend on the number of terms in the series, that is, on the number of radiators used. The coefficients A_n , B_n , C_n , and D_n , can be determined in any manner; however, the Fourier approximation is significantly easier to compute since each added term is independent of earlier terms. Thus,

$$A_n = \frac{1}{l} \int_{-l}^l f_{i,e}(\theta) \cos \frac{(n+\frac{1}{2})\pi\psi}{l} d\psi$$

$$B_n = \frac{1}{l} \int_{-l}^l f_{r,o}(\theta) \sin \frac{(n+\frac{1}{2})\pi\psi}{l} d\psi$$

$$C_n = \frac{1}{l} \int_{-l}^l f_{r,e}(\theta) \cos \frac{n\pi\psi}{l} d\psi$$

$$D_n = \frac{1}{l} \int_{-l}^l f_{i,o}(\theta) \sin \frac{n\pi\psi}{l} d\psi$$

To check orthogonality, it is noted that

$$I = \int_{l=-1}^{l=1} \cos(n+\frac{1}{2})\pi\psi \left\{ \begin{array}{l} \sin(m+\frac{1}{2})\pi\psi \\ \cos(m+\frac{1}{2})\pi\psi \end{array} \right\} d\psi = 0, \quad m+n$$

It can be mathematically proved that this decomposition is sufficient to describe any arbitrary pattern $f(\theta)$.

$f(\theta)$ has been developed in a least square approximation in $\psi = \sin \theta$. If a least square approximation in θ is wanted a system of equations must be evaluated where integrals like

$$c \int_{-l}^l f(\theta) \sin \left[\frac{n\pi}{l} \sin \theta \right] d\theta$$

are typical. These can usually be expressed in Bessel or Struve functions when $f(\theta)$ is simple.

Only when $l=1$ or $d=\lambda/2$ will the expansion interval agree with the physical interval $-90^\circ \leq \theta \leq 90^\circ$. When $l>1$, $d<\lambda/2$, part of $f(\theta)$ will not be visible. When $l<1$, $d>\lambda/2$, $f(\theta)$ will start repeating when $\theta = \sin^{-1}l$.

Experimental efforts in the application of the method of the invention to the double-step function can be illustrated by the representations of the ideal function shown in FIGURE 3. Both waveguide and two-wire line-feeding systems have been used, while the double-step function was selected because it minimized the number of spaced elements and their resulting mutual couplings.

The pattern in FIGURE 3 can be thought of as made up of a cosine symmetric main lobe and a step function on one side of the $\theta=0$ axis. To simplify the design $f_w(\theta)$ produces the main lobe and a combination of $f_v(\theta)$ and $f_u(\theta)$ produces the step function. Both odd and even patterns are thereby obtained in phase quadrature where they do not destructively interfere with each other.

As a first step, suppose f_v produces an odd function as shown in dotted lines in FIGURE 4, the even function being displayed in solid lines. Then

$$\begin{aligned} f_v &= \sum_{n=0}^{n=N} B_n \sin \frac{(n+\frac{1}{2})\pi\psi}{l} d\psi \\ B_n &= \frac{1}{l} \int_{-l}^0 -\frac{1}{2} \sin \frac{(n+\frac{1}{2})\pi\psi}{l} d\psi + \frac{1}{l} \int_0^l \frac{1}{2} \sin \frac{(n+\frac{1}{2})\pi\psi}{l} d\psi \\ &= \frac{1}{l} \int_0^l \sin \frac{(n+\frac{1}{2})\pi\psi}{l} d\psi \\ &= \frac{1}{(n+\frac{1}{2})\psi} \end{aligned}$$

$$\begin{array}{ll} n=0 & B_0 = 2\pi = 0.6366 \\ n=1 & B_1 = \frac{2}{3}\pi = 0.2122 \\ n=2 & B_2 = \frac{2}{5}\pi = 0.1273 \\ n=3 & B_3 = \frac{2}{7}\pi = 0.09095 \end{array}$$

Note that when $f_u(\psi)$ generates a constant function equal to $\frac{1}{2}$, the series reduces to one term, $C_0 = \frac{1}{2}$.

f_w represents the peak of the pattern and can be computed according to Dolph-Tchebycheff theory of linear arrays to give

$$f_w(\psi) = 3.259 \cos 90^\circ k\psi + 2.170 \cos 270^\circ k\psi + .868 \cos 450^\circ k\psi$$

which represents the formula with coefficients normalized to present the peak 16 db above the step function.

Now, to produce a step function of unity amplitude in the interval between $0 \leq \theta \leq 90^\circ$ and approximately zero in the interval $0 \geq \theta \geq -90^\circ$, one can write for the first seven radiators:

$$f_{\text{step}} = f_v + f_u = 0.5 + 0.636 \sin 90^\circ k\psi + 0.213 \sin 270^\circ k\psi + 0.128 \sin 450^\circ k\psi$$

where $k = \lambda_g/\lambda$. The total pattern equals the sum of f_u , f_v and f_w . The first slots on each side of the phase reference center are spaced $\lambda_g/4$, and all other slots are spaced $\lambda_g/2$. An illustration of an array with a feeding input or bolometer F and matched load L for producing such a single-step pattern is shown in FIGURE 5; pattern results are shown in FIGURE 6. The slots of the embodiment are oriented in the same direction to achieve the same polarization. By placing the center slot on the opposite side of the center line the pattern could be reversed. In FIGURE 5, slots S1, S2, and S3 are at one quarter wavelength spacing while radiators S4, S5, S6, and S7 are at half wavelength spacing.

The slot coupling to the waveguide is controlled by transverse spacing. The couplings and transverse spacings can be directly calculated once the relative radiated power at each longitudinal point is known. The field (E) of each elemental slot is combined at radiating points to get the sum field and field squared, which represents power (P). The combined pattern distribution, which

results from the pattern distribution of each of the elements, produces the total field of the final array.

Thus, it can be seen that by assuming a desired pattern, dividing it into odd and even functions, determining the relative radiating power of the elements, combining all elements of the same longitudinal spacing in accordance with the final power distribution, and choosing elements coupling to the transmission line according to the calculated power distribution; an antenna design will result with at least one radiator having approximately one quarter wavelength spacing. The invention is applicable to any array of radiating elements where there is 180° phase reversal with respect to a feeding transmission line, for example, with a balanced two-wire line and dipoles connected thereto.

Although the invention has been described with reference to a particular embodiment, it will be understood to those skilled in the art that the invention is capable of a variety of alternative embodiments within the spirit and scope of the appended claim.

I claim:

A method of controlling the radiation pattern established by an antenna array which comprises the steps of choosing a radiation pattern corresponding to a Fourier series of odd and even functions, and causing radiation to occur along said array at positions such that the energy

amplitude at each position conforms to an element of said Fourier series in such manner as to provide a pattern summation corresponding to the quarter wavelength summation value of said series.
